UNITED STATES PATENT OFFICE

171,128

DIAPER COVER OR THE LIKE

William H. Goldstein, Atlanta, Ga.

Application March 11, 1953, Serial No. 23,994

Term of patent 14 years

(Cl. D3—17)

To all whom it may concern:

Be it known that I, William H. Goldstein, a citizen of the United States, residing in the city of Atlanta, county of Fulton, State of Georgia, have invented a new, original, and ornamental Design for a Diaper Cover or the like, of which the following is a specification, reference being had to the accompanying drawing, forming part thereof:

Fig. 1 is a front elevation of a diaper cover showing my new design;

Fig. 2 is a rear elevation of the diaper cover shown in Fig. 1; and

Fig. 3 is a side elevation thereof.

I claim:

The ornamental design for a diaper cover or the like, as shown.

WILLIAM H. GOLDSTEIN.
